UNITED STATES PATENT OFFICE.

ROBERT E. JACKSON AND EDWIN M. JENKINS, OF PRINCETON, WEST VIRGINIA.

FLUE BLOWER.

Application filed November 16, 1921. Serial No. 515,619.

To all whom it may concern:

Be it known that we, ROBERT E. JACKSON and EDWIN M. JENKINS, citizens of the United States, residing at Princeton, in the county of Mercer and State of West Virginia, have invented certain new and useful Improvements in Flue Blowers, of which the following is a specification.

This invention relates to improvements in flue blowers and more particularly to a device adapted to be attached to a boiler whereby any selected flue may be cleaned as desired.

In a prior Patent No. 1,416,209, granted May 16, 1922, we have disclosed and claimed a flue blower in which a rotatable support is arranged within the fire box and a flue cleaning device is transversely mounted on said support and adapted to be alined with the end of the flue to be cleaned. In the present invention, we have provided a flue cleaner in which movable parts within the boiler are eliminated. A plurality of headers are arranged transversely of the smoke box mounted on suitable supports, a header being provided for each horizontal row of flues. The headers are provided with a plurality of lead lines or pipes arranged therein communicating with the individual flues of the row. Each of the headers is connected to a suitable supply of compressed air, steam, or other compressed fluid and means are provided for feeding the fluid to any selected pipe within the header.

The valve mechanism whereby any desired connecting pipe is connected to the source of supply is arranged on the outside of the boiler and is readily accessible at all times.

In the accompanying drawings, we have shown one embodiment of the invention. In this showing:

Figure 1 is a longitudinal sectional view of a portion of a boiler showing the invention applied,

Figure 2 is a transverse vertical sectional view on line 2—2 of Figure 1,

Figure 3 is a side elevation of a portion of the boiler showing the valve arrangement,

Figure 4 is a detail view of a portion of the header,

Figure 5 is an end elevation thereof,

Figure 6 is a detail view of the header valve casing, parts being shown in section,

Figure 7 is a plan view of one of the headers,

Figure 8 is a sectional view on line 8—8 of Figure 6, and,

Figure 9 is a detail view of the inner end of one of the connecting pipes.

Referring to the drawings, the reference numeral 1 designates the smoke box of a boiler and 2 the front flue sheet. The boiler disclosed is the locomotive type, but the invention may be employed with any type of fire tube boiler. A plurality of flues 3 extend through the flue sheet in the usual manner.

The flue blower forming the subject matter of the invention consists of a plurality of headers 4 arranged transversely of the smoke box and in horizontal alinement with each row of flues. One end of the header is provided with grooves 5 for the reception of brackets 6 secured to the wall of the boiler. The opposite end of the header extends through an opening in the opposite side of the boiler and is supported by means of suitable brackets. As shown, this end of the header is enlarged, as at 7, the body portion and the enlargement being provided with flanges 8 adapted to receive bolts 9 by means of which the sections are held together. The enlarged end of the header is provided with a flange 10 forming a seat for the valve casing 11, the valve casing being retained in position by means of suitable fastening means 12. A disk valve 13 having an opening 14 is arranged within the valve casing. The disk valve is provided with a stem 15 having an inner squared end 16 adapted to be received in a recess in the upper face of the valve. The portion of the valve stem passing through the casing is circular in shape, as at 17, and the outer end of the stem is square, as at 18. A plate 19 is arranged on the valve casing, the plate being provided with a circular opening for the passage of the circular portion 17 of the valve stem. This plate is provided with a plurality of notches 20 arranged about its periphery. A handle 21 is arranged on the squared portion of the valve stem and re-

tained in position by means of a pin 22. The handle extends beyond the plate 19 and is provided with a plunger 23 arranged in a recess and normally retained in position 5 by means of a spring 24.

A plurality of connecting pipes 25 are arranged within the header, the number of connecting pipes in each header corresponding to the number of flues in the horizontal 10 row. The ends of these pipes within the enlarged portion 7 are arranged concentrically in alignment with the opening 14 in the valve. The connecting pipes 25 extend longitudinally of the header to a point in 15 alignment with the flues to which they are to be connected and are then offset, as at 26, and extend through the front of the header. The pipes or passages 25 are provided with lead pipes 27 extending into the end of the 20 flues (see Figure 1). These lead pipes are provided with flared ends 28, the flared portion extending downwardly to direct the blast of steam or air against the lower wall of the flue and insure perfect distribution 25 of the cleaning fluid within the flue.

The operation of the device is as follows:

When a flue is to be cleaned, the valve is turned to connect the valve casing with the proper pipe or passage 25. Steam, compressed air or other suitable fluid is introduced into the valve casing through a pipe 29 which may be provided with a suitable valve (not shown) whereby the supply of fluid to the valve casing may be controlled. 30 The position of the opening in the disk valve 13 may be determined by suitable indicia arranged on the plate 19 and disposed adjacent the notches 20. The plate will be provided with one more notch than the 35 number of flues in each row, and one position of the handle 21 will indicate that the valve opening 14 is out of alignment with the pipes or passages 25, the other positions indicating that the valve opening is in 40 alignment with one of the passages to direct fluid to a given flue. The fluid passing through the opening in the valve and the pipe or passage 25 is directed to the lead pipe 27 thence to the interior of the flue. 45

It is to be understood that the form of our invention herewith shown and described is to be taken as a preferred example of the same, and that various changes in the shape, size, and arrangement of parts may be resorted to without departing from the spirit 50 of the invention or the scope of the subjoined claims.

Having thus described our invention, we claim:

60 1. A flue blower adapted to be arranged transversely of a boiler in alignment with a row of flues, and being provided with a plurality of passages corresponding in number to the number of flues, means for 65 connecting said passages to the ends of the

flues, a pipe connected to a source of compressed fluid, and means for connecting any one of said passages to said pipe.

2. A flue blower comprising a header arranged transversely of the smoke box of 70 a boiler in alignment with a row of flues, said header being provided with a plurality of passages corresponding to the number of flues, a connecting pipe connecting each of 75 said passages to one of said flues, a valve 80 casing arranged adjacent one end of said header, said valve casing being connected to a source of fluid supply, and means for connecting any one of said passages to said valve casing.

3. A flue blower comprising a header arranged transversely of the smoke box of a 85 boiler, said header being provided with a plurality of passages, a connecting pipe connecting each of said passages to one of said flues, a valve casing arranged on the end of 90 said header, a disk valve arranged in said valve casing, said disk valve being provided with an opening adapted to be arranged in registration with the end of a selected one of said passages, and means for supplying fluid to said valve casing.

4. A flue blower comprising a header adapted to extend transversely of the smoke 95 box of the boiler, said header being provided with a plurality of passages, a connecting pipe secured to said header adjacent the end of each passage and connecting said passage to one of the flues of the boiler, a valve casing arranged on the end of said 100 header, a valve arranged in said casing to control the communication between said valve casing and said passages, and an indicator arranged on said valve to indicate the passage that is in communication with the 105 valve casing.

5. A flue blower comprising a header arranged transversely of the smoke box of a boiler, and in alignment with a row of flues, said header being provided with a plurality 110 of passages corresponding in number to the number of flues, means for connecting each of said passages to a corresponding flue, the end of said header being enlarged, said passages extending through said enlarged portion and being concentrically arranged, a valve member arranged adjacent said enlarged end, said valve member being capable of rotation and provided with an opening 115 adapted to register with the end of said 120 passages, and a pipe connected to a source of fluid adapted to supply fluid to the passage aligned with the valve.

6. A flue blower comprising a header arranged transversely of a boiler, said header 125 being provided with a plurality of passages corresponding in number to a row of flues within the boiler, means for connecting each of said passages to a corresponding flue, the end of said header being enlarged, said pas- 130

sages being extended through said enlarged portion and arranged concentrically, a valve casing adjacent the end of said header, and a rotary valve arranged therein, said valve being provided with an opening registering with the ends of said passages whereby a selected passage may be placed in communication with the valve casing.

In testimony whereof we affix our signatures in presence of two witnesses.
